UNITED STATES PATENT OFFICE.

EDWARD C. MURRAY, OF OKLAHOMA, OKLAHOMA.

NON-REFILLABLE BOTTLE.

1,223,720.

Specification of Letters Patent. Patented Apr. 24, 1917.

Application filed February 16, 1916. Serial No. 78,611.

To all whom it may concern:

Be it known that I, EDWARD C. MURRAY, a citizen of the United States, residing at Oklahoma city, in the county of Oklahoma and State of Oklahoma, have invented certain new and useful Improvements in Non-Refillable Bottles, of which the following is a specification.

This invention relates to improvements in non-refillable bottles, one object of the invention being the provision of a commercially non-refillable bottle, which is simple and inexpensive to manufacture and fill, and which after being once filled and emptied cannot be refilled.

A further object of this invention is the provision of a non-refillable bottle, in which the body at the junction between it and the neck is provided with a valve seat for the reception of a loose ball valve, there being mounted in the outlet of the neck, means to prevent tampering with the ball valve, and also a limiting means and housing for the ball valve.

25 In the accompanying drawings:—

Figure 1 is a vertical central sectional view of the complete neck of the bottle with the non-refillable elements in position.

Figs. 2 and 3 are details of various parts.

30 Referring now, more particularly, to the accompanying drawings in which similar reference numerals designate like and corresponding parts throughout the several views, I provide a bottle body 5 having a neck issuing therefrom and provided adjacent its inner end with an inverted conical chamber

6 the apex of which serves as a valve seat 7, for the reception of the ball valve 8 while the base of the chamber provides a relatively 40 wide shoulder or stop for the valve when the bottle is inverted. The valve may be made of any desired material, and may be hollow or solid, as may be found necessary, but must have sufficient weight to fit snugly but 45 not fixedly upon the seat.

The outlet or outer portion 9 of the neck is of sufficient size to permit of the introduction of the ball valve therethrough, the bottle being filled with the contents, before the ball

valve is inserted in the neck to sit upon its 50 seat.

The guard member or tube 10 is now snugly fitted in the outer portion of the neck outlet, so as to house the ball valve, and as the screen 11 is carried by the inner end of 55 the tube, no tool or implement may be projected therein to tamper with the ball valve. Likewise, the screen prevents the ball from completely closing the tube. The flange 12 of the tube is cemented to the outer face of the 60 annular exteriorly extending rib on the outer end of the neck, so that it is impossible to remove the same without destroying the bottle.

From the foregoing description taken in 65 connection with the drawings, it is evident that a very simple and inexpensive construction of a non-refillable bottle is produced, the same being so constructed as to permit of the easy filling of the bottle and 70 the sealing thereof.

In the inner face of the base of the inverted conical chamber 6, leading from the outlet are one or more radial grooves 13, which act as a drain at this point. 75

It will be noted that the chamber 6 may contain liquid, and that the ball valve when seated will retain the liquid therein, the liquid and the valve thus making it impossible for the admission of air to the bottle. 80 It is also apparent that the ball must be a true sphere, and that the seat must be ground to a true fit therewith; and also that all the various parts are preferably composed of glass. 85

What I claim, as new, is:—

A non-refillable bottle including a body having a neck issuing therefrom, an annular rib formed exteriorly at the mouth of the neck and having a flat outer face, the neck being enlarged adjacent the bottle body to provide an inverted conical chamber the apex of which serves as a valve seat while the base forms a relatively wide annular stop, a ball valve insertible in the chamber 90 and normally resting on the seat and adapted to engage the stop when the bottle is inverted, an imperforate tube snugly fitted in

the outer portion of the neck and terminating at the inner end of the outer portion of the neck, an annular flange formed exteriorly on the outer end of the tube and
5 connected to the outer face of the rib so as to be supported by the rib, and a perforated

disk mounted at the inner end of the tube to prevent the bottle valve from completely closing the tube so as to consequently permit of liquid passing through the tube.

In testimony whereof I affix my signature,
EDWARD C. MURRAY.
